Primary Examiner — George D. Kirschbaum*Assistant Examiner* — Lacey Chey Bowman(74) *Attorney, Agent, or Firm* — Quarles & Brady LLP(57) **CLAIM**

The ornamental design for a videoconferencing camera as shown and described.

DESCRIPTION

FIG. 1 is a top, front, right perspective view of a videoconferencing camera showing our new design;

FIG. 2 is a bottom, front, left perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines in the drawings are for the purpose of illustrating portions of the videoconferencing camera that form no part of the claimed design.

1 Claim, 8 Drawing Sheets(56)
